UNITED STATES PATENT OFFICE.

HARRY HUGHES, OF SAXONVILLE, MASSACHUSETTS, ASSIGNOR TO ROXBURY CARPET COMPANY, OF BOSTON, MASSACHUSETTS, A CORPORATION OF MASSACHUSETTS.

TUFT-PILE-FABRIC LOOM.

1,363,790.

Specification of Letters Patent. Patented Dec. 28, 1920.

Application filed July 23, 1920. Serial No. 398,490.

To all whom it may concern:

Be it known that I, HARRY HUGHES, a citizen of the United States, and a resident of Saxonville, county of Middlesex, and State 5 of Massachusetts, have invented an Improvement in Tuft-Pile-Fabric Looms, of which the following description, in connection with the accompanying drawings, is a specification, like characters on the drawings representing like parts.

This invention relates to looms and more particularly to looms for weaving tufted pile fabrics such, for instance, as moquette carpets or rugs or other types of fabrics in 15 which the pile forming yarns are passed about weft threads in the body of the fabric with their ends projecting to form the tread surface, and the present invention relates more especially to means for cutting the pile 20 forming yarn after the same has been placed in the fabric.

In this general type of loom, the tuft yarns are usually carried on spools which are mounted upon suitable chains or carriers, 25 and yarns are taken from these spools by presenting devices and passed about weft threads which form part of the body of the fabric, and then the tuft yarns are cut or trimmed by suitable knives operating at a 30 distance above the body of the fabric.

The tuft yarns to be placed in the fabric are usually carried by spools in such a manner that each spool has a number of yarn ends extending therefrom in a row, and these 35 yarns are introduced into the fabric during the weaving operation to form the tuft or pile of the fabric. After each row of yarns is placed in the fabric and secured about the weft threads, it is necessary to cut the tufts 40 between the fabric and spool.

The primary object of the present invention, therefore, is to improve the construction and operation of the cutting mechanism which cuts or trims the tuft yarns and severs 45 them from the source of supply. In addition to the above, other objects and features of the invention will be described in connection with the accompanying drawings, which illustrate a good, practical form of the invention, the details of which may be modified 50 within the true scope thereof, as defined by the claims.

In the drawings:

Figure 1 is a sectional side elevation of a 55 tuft pile fabric loom, some of the parts be-

ing omitted, and having the present invention associated therewith;

Fig. 2 is an enlarged perspective view of a portion of the loom showing the mechanism for successively moving the spools into position to present their tuft yarns to the fabric; 60

Fig. 3 is an enlarged perspective view of part of the knife operating mechanism;

Fig. 4 is an enlarged plan view showing the cutting knives and their relative movements; and

Fig. 5 is a perspective view of part of the spool delivery mechanism.

The loom frame may be of suitable construction for supporting the operating parts, 70 and comprises the side frames 1 tied together with suitable cross ties 2. Supported upon suitable brackets 3, 4, at the rear of the loom are bearings for supporting the stuffer and binder warp beams, the former 75 being indicated at 5 and the latter at 6. Also mounted upon the bracket 7 extending from the loom frame is the beam 8 for the selvage thread. The binder warp threads *a* from the beam 6, pass forwardly about the 80 tension rolls 9 over and under the lease rods 10 and through the harnesses 11 and 12 which may be actuated by suitable operating mechanism, as usual in this class of looms. The means for actuating the binder warp harnesses 11 and 12 form no part of the present 85 invention and the construction and mode of operation, therefore, of such means, is not herein illustrated.

The stuffer warp threads *b* pass about suitable guiding and tension rods 13, Fig. 1, and then through a stationary or fixed harness 14, the construction being such that in the formation of the sheds the binder warps are raised and lowered relatively to the fixed 90 stuffer warps.

The selvage thread *c* passes from the beam 8 directly through the selvage thread heddle 15 which is raised and lowered through mechanism that will hereinafter be described. 100

The various warp threads so far described pass forward through the usual reed 16 and are united at the fell of the cloth 17, Fig. 2, the construction being such that upon proper 105 manipulation of the shedding mechanism either an upper and lower or double shed, or a single shed will be formed.

The reed 16 may be appropriately operated, as is common in this class of looms in 110

order to beat up the weft threads to the fell of cloth, but since such operating mechanism forms no part of the present invention, its illustration is not deemed necessary.

5 To one side of the loom are mounted a pair of weft carrying needles 18 and 19 the forward ends of which are slidably mounted in a block 20. The needles 18 and 19 are slid into and out of the shed by mechanism not shown, to carry the weft threads into the sheds.

As above stated, in the type of loom to which this invention relates, the tuft yarns are usually carried on spools, and the spools 15 are moved into position to introduce the ends of the yarn carried thereby into the fabric. One type of mechanism well known by those skilled in the art, has been illustrated for carrying out this operation, and will now be 20 described. Above the loom frame is mounted a shaft 21 supported by brackets 22 carried by the loom frame. The shaft 21 is provided with spaced sprocket wheels 23 only one of which is shown in the drawings. The spools 25 24 which carry the tuft yarns are sufficiently long to extend across the strip of fabric being woven and are carried between spaced sprocket chains 25 which pass about the sprocket wheels 23. Each spool 24 carries a 30 large number of yarn threads or strands and the end of each yarn thread is led through a presenting device 26 and extends a short distance beyond the same as indicated at 27. Each spool 24 and the accompanying row of 35 presenting devices 26 is carried by a frame 28 which in turn is removably secured to a link of each of the sprocket chains 25. The yarn threads may be differently colored and arranged on the spools.

40 As each spool in passing about the sprocket wheel 23 reaches a predetermined position, its frame 28 with the spool therein is disengaged from the sprocket chain and moved toward the fabric, as shown in Fig. 2. For 45 this purpose, any of the well known mechanisms may be employed, but in the present instance upon each side of the loom is mounted a swinging arm 29, to the outer end of which is secured a trough shaped carrier 30. 50 When the frame 28 is moved to a predetermined position about the sprockets, the carriers 30 are moved upward by the arms 29 so that the trough of each carrier is slid over an end of a frame 28, and the frame is secured in the carriers by the pin 31. Then as 55 the arms 29 are moved downward toward the fabric, the frames 28, which are removably secured by spring clips or the like to the sprocket chain, are pulled away from the 60 sprocket chain and are moved into position to introduce the yarn ends 27 between the warp threads. As soon as the yarn ends 27 have been secured in place within the fabric, the cutting knives, to be described, are operated to cut the tufts of yarn from their 65

source of supply, after which the arms 29 and coöperating parts move the frame 28 back to the position in which it is supported by the sprocket chains.

The mechanism so far described does not 70 form part of the present invention, and has been described only to the extent that is thought necessary to make clear the construction and operation of the cutting mechanism used in connection therewith. The 75 improved cutting mechanism will now be described.

This means consists of two knives, one of which, the rear knife in this instance, is moved in a straight path, from end to end, 80 and the other of which is moved with a differential or shogging motion relative to its companion knife in order to cut the tuft yarns progressively with a slicing or shearing cut.

In the present instance of the invention, the loom frame has mounted thereon the rock shaft 32, Fig. 1, from which rises the two side arms 33 carrying at their upper end the straight edge knife 34 which may be appropriately secured in adjusted position on the arm 33 by suitable bolts 35. Extending downwardly from the shaft 32 is the arm 36 connected by a link 37 with the upper end of an operating member 38 pivoted to the loom frame at 39, and having a roller 40 which bears upon the periphery of a cam 41 secured to the shaft 42, the construction being such that the cam 41, of which there may be two, one at each side of the loom on the shaft 42, 100 actuate the side arms 33 to move the knife 34 downwardly to its predetermined cutting position, and in order that this cutting position may be accurately determined, the side arm 33 has connected thereto the link 43, which is provided with an adjusting screw 44 which, when the knife 34 is in its cutting position, contacts with a stop 45 secured to a fixed portion of the loom.

The other cutting member is arranged 110 frontwardly of the straight edged knife, just described, and its two end portions are actuated by side arms which have differential or movements non-currently. In the present instance the side arms 46, only one 115 of which is shown in Fig. 1, are mounted to rock upon a shaft 47 and each has a downwardly extending arm 48. Secured to the cam shaft 49, are the two side cams 50 and 51. The side arms 48 each carry rolls 52, 120 the rollers of one of said arms being actuated by the cam 50 and the roller of the other of said arms being actuated by the cam 51. Since the cams 50 and 51 are offset on the shaft 49, as indicated in Fig. 1, it 125 follows that one end of the front knife will move in advance of the other end, and then the other end will catch up with the first end during the cutting operation of the knife. The upper end of each arm 46 is forked as 130

shown in Fig. 3, and has a link 53 pivotally secured within the fork. The opposite end of the link 53 is pivotally secured to the downwardly extending leg 54 of a bracket 55, and this bracket, in the present instance is pivotally secured as at 56 to the under face of the knife 57. The ends of this knife are slidably supported in the slotted brackets 58 which may be adjustably mounted upon the opposite sides of the loom. The knife 57 is best shown in its three positions in Fig. 4. The full line position of the knife 57 indicates that the edge of the knife near one end thereof is straight, but toward the other end thereof, at 59, the knife curves frontwardly. The dotted line position of the knife 57 indicates that the advancing edge at the right has commenced the cut of a row of tufts and is nearing a point where that end of the knife comes to rest. The other end of the knife at the left, Fig. 4, continues to move frontwardly from the dotted to the dot-and-dash line position wherein it will be apparent that the knife is moved with a shearing cut from one end of its companion or straight edge knife to the other. The pivotal connections 56 between the knife 57 and the brackets 55 permit one end of the knife to be freely advanced ahead of its other end, and to further provide for the differential or shogging movement of the knife 57, sufficient clearance, as at 60, is provided between the ends of the knife 57 and the inner wall within the slotted bracket 58 to allow free movement of the knife.

In the loom construction illustrated, the weft thread is carried into the shed by relatively long needles 18 and 19 and since the needles are inserted in and drawn out of the same shed, it is necessary to provide mechanism at each side of the loom to engage the weft or needle thread and form a selvage. This selvage may be formed at the left hand side of the cloth by selvage shuttle mechanism, and the selvage is formed at the right-hand side of the cloth by the selvage heddle 15 hereinbefore referred to. The selvage heddle 15 has the single eye for the passage of the selvage thread *c* and extends upwardly into engagement at 61, Fig. 1, with a rocking lever 62 pivoted to the loom frame at 63 and actuated by the rod 64, the lower end portion of which is connected at 65 to one arm of a bell crank lever pivoted to the loom at 66. The other arm 67 of the bell crank is operatively engaged with the link 43, heretofore described as connected to the knife supporting side arm 33. The construction is such that the selvage heddle will be raised and lowered in timed relation with the needle operation to interlock with the weft threads at the needle side of the cloth and form the selvage, while the selvage at the opposite side of the cloth will be formed by the selvage shuttles, as above mentioned.

The operating parts of the loom are so timed that after each insertion of a row of tuft yarns within the cloth, the knives operate to progressively cut or shear these tufts from the yarns carried by the spool, and as 70 the cloth is woven it passes to the take-up rolls 68 in a well-known manner.

Claims:

1. In a tuft pile fabric loom, the combination of shedding mechanism, needles for inserting weft threads for holding the tuft yarns, two knives for cutting the tuft yarns, one of said knives being movable throughout its length simultaneously to the cutting position, and the other of said knives having 80 its ends advanced one ahead of the other to cut the tuft yarns progressively from one end of a row to the other, and means for operating the knives.

2. In a tuft pile fabric loom, the combination of shedding mechanism, needles for inserting weft threads for holding the tuft yarns, two knives for cutting the tuft yarns, one of said knives being movable throughout its length simultaneously to the cutting position, and the other of said knives being provided with an edge curved frontwardly at one end and having its ends advanced differentially toward the other knife to cut the tuft yarns progressively from one end of a 95 row to the other, and means for operating the knives.

3. In a tuft pile fabric loom, the combination of shedding mechanism, two needles for inserting weft threads simultaneously, two knives for cutting the tuft yarns, means for moving one of said knives uniformly from end to end to the cutting position, a stop for determining the cutting position of the knife, and means for operating the other knife differentially by moving one end in advance of the other to progressively cut the tufts from one end of a row to the other.

4. In a tuft pile fabric loom, the combination of shedding mechanism, two knives for cutting the tuft yarns, means for operating the knives, a selvage heddle carrying a selvage thread, and means connected to one of the knives for operating the selvage heddle.

5. In a tuft pile fabric loom, the combination of shedding mechanism, means movable toward and from the plane of warp threads for inserting a row of tuft yarns into the shed, means for inserting weft threads to hold the tuft yarns, two knives for cutting 120 the tuft yarns, one of said knives being movable throughout its length simultaneously to the cutting position, and the other of said knives having its ends advanced one ahead of the other to cut the tuft yarns progressively from one end of a row to the other, and means for operating the knives.

6. In a tuft pile fabric loom, the combination of shedding mechanism, spools carrying tuft yarns, presenting devices for inserting 130

- a row of tuft yarn into the shed, means for inserting weft threads to hold the tuft yarns, two knives for cutting the tuft yarns from their source of supply, one of said knives 5 having its ends advanced one ahead of the other toward the other end to cut the tuft yarns progressively from one end of a row to the other, and means for operating the knives.
- 10 7. In a tuft pile fabric loom, the combination of shedding mechanism, means for placing a row of tuft yarns in the shed, needles for inserting weft threads for holding the tuft yarns, two knives for cutting the tuft 15 yarns, means for advancing first one end and then the other end of one of said knives toward the other knife to progressively cut the tuft yarns from one end of a row to the other.
- 20 8. In a tuft pile fabric loom, the combination of shedding mechanism, means for placing a row of tuft yarns in the shed, needles for inserting weft threads for holding the

tuft yarns, two knives for cutting the tuft 25 yarns, guides for the opposite ends of one knife arranged to guide the same toward and from the other knife, differently timed cams for operating the guided knife, and means for imparting the movement of said cams to the respective ends of said knife to 30 advance the ends of the knife differentially and progressively cut the tuft yarns from one end of a row to the other.

9. In a tuft pile fabric loom, the combination of cutting mechanism, knives for cutting the tuft 35 yarns, means for operating the knives to cut a row of tuft yarns progressively from one side of the fabric to the other, a selvage heddle carrying a selvage thread, and connections between the selvage 40 heddle and one of the knives for operating the selvage heddle.

In testimony whereof, I have signed my name to this specification.

HARRY HUGHES.
